UNITED STATES PATENT OFFICE.

STUART W. WALKER AND EDWARD B. HORNER, OF MARTINSBURG, WEST VIRGINIA.

FIRE-ESCAPE.

SPECIFICATION forming part of Letters Patent No. 643,575, dated February 13, 1900.

Application filed August 3, 1899. Serial No. 726,050. (No model.)

To all whom it may concern:

Be it known that we, STUART W. WALKER and EDWARD B. HORNER, citizens of the United States, residing at Martinsburg, in the county of Berkeley and State of West Virginia, have invented new and useful Improvements in Fire-Escapes, of which the following is a specification.

This invention relates to fire-escapes, and particularly to that class of fire-escapes where in a sling adapted to be secured to the person is suspended from a friction device arranged to slide down a rope or cable, the friction device being under the control of the person descending the rope, whereby the speed of the descent may be regulated.

The invention has for its object, first, to provide in a device of the character described improved means for returning it after a descent has been made to place it in readiness for another descent, to provide an improved friction-brake for regulating the speed of the descent, to provide improved means for automatically bringing the device to a stop in case the operator loses control of it or neglects to operate the brake, to provide means for preventing excessive wear or chafing of the cable, and to improve and simplify the construction and render more safe, certain, and efficient this class of fire-escapes generally.

To these ends our invention consists in the features and in the construction, combination, and arrangement of parts hereinafter described, and particularly pointed out in the claims following the description, reference being had to the accompanying drawings, forming a part of this specification, wherein—

Figure 1 is a perspective view of the device in operative position. Fig. 2 is a longitudinal vertical sectional view of the same, and Fig. 3 is a front elevation of the fire-escape device.

Referring to the drawings, the numeral 1 indicates a frame or casing comprising a rectangular frame 2, recessed upon its inner side, as at 3, and a cover-plate 4, bolted to the frame 2 by means of bolts or screws 5. Journaled in the sides of the casing, one above the other, are journals or short shafts 6, on which are journaled grooved pulleys 7. Apertures 8 and 9 and 8^a and 9^a are formed in the top and bottom of

the casing, through which is passed an endless cable, (indicated by the numerals 10 and 11,) the portion 10 of said cable being led alternately around the opposite sides of the pulleys 7. Guide-pulleys 12 and 13 are arranged adjacent to the apertures 8 and 8^a to lead the cable about the pulleys and prevent it from chafing against the sides of the apertures. The other portion 11 of the cable passes through the casing and through the apertures 9 and 9^a, and also passes between one side of the casing and a pivoted cam 14, having a serrated engaging face, as shown. The cam is normally caused to engage the cable by a leaf-spring 15, one end of which is inserted in a kerf 16, cut in the end of the casing, and its other end bears against a shoulder 17, formed on the cam. A dovetailed recess 18 is formed in the side of the casing opposite the cam 14, and in said recess is fitted a wear-block 19, formed of wood or other suitable non-abrading material, against which the cable impinges when pressed thereagainst by the cam. The purpose of the wear-block is to prevent the cable from being unduly chafed, abraded, or worn. In the bottom of the casing is firmly fixed a ring 20, to which is attached a seat or sling 21, in which a person may seat himself, and a strap 22 is also preferably secured there- to intermediate its ends and is adapted to be fastened around the body of the person seated in the sling.

The lower end of the casing is rounded, as at 23, and in the opposite sides of said end are secured staples 24. From said staples is loosely suspended a hand friction-brake comprising two parallel arms or members 25, pivotally connected together near their lower ends by metallic straps 26. The adjacent faces of the arms 25 above their pivotal point are flat or straight, and to said faces are secured by screws 26^a or any other suitable means wear-strips 27, formed of wood or similar non-abrading material. The wear-strips 27 are longitudinally grooved on their inner or adjacent faces, as shown, to receive and embrace the portion 10 of the cable. The adjacent faces of the arms below the pivotal point are grooved and corrugated, and one of said faces is preferably transversely serrated, as at 28, to cause the arms to firmly grasp the

cable. The upper ends of the arms 25 diverge outwardly, as at 29, and at their extremities extend laterally in opposite directions, as at 30, forming lugs, by means of which the friction-brake is loosely suspended from the staples 24. The portion 10 of the cable after it leaves the casing passes between the grooved wear-strips and between the corrugated lower ends of the pivoted arms, 5 and said cable should be of sufficient length to reach the ground. The endless cable at its upper end passes about a pulley 29^a, which may be attached by means of a rope 30^a to any convenient support in such manner as to 10 hang over the window-sill.

The operation of the device will be readily understood. The person seeking to escape seats himself in the sling and fastens himself securely therein by the strap 22. Then 15 by grasping the arms 25 of the brake in his hand he may regulate the speed of his descent by causing the wear-strips on the arms to impinge with more or less force against the portion 10 of the cable. The brake-arms normally grasp the rope with a certain amount 20 of force or friction, and hence when a person seats himself in the sling suspended from the casing the latter has a slight downward movement, while the brake remains stationary. 25 This results in the rounded or wedge-shaped lower end of the casing being forced between the diverging upper ends of the brake members, thereby spreading said ends apart and forcing their lower ends toward and against 30 the cable. By these means the entire device is held stationary, giving the person seeking to escape ample time to strap himself securely in the sling and collect himself, after which he grasps the brake members, and by 35 pressing them together causes them to impinge with more or less force against the rope or cable, and thus regulates the speed of his descent. So should the person through excitement or inadvertence lose control of the 40 brake the casing will operate to spread apart the diverging ends of the brake members and cause their lower ends to grasp the cable and stop the descent until he has had time to regain control of the brake. In descending, 45 the friction-pulleys about which the cable is alternately passed operate to retard the descent of the device and the portion 11 of the cable has a tendency to be drawn up through the casing. This tendency, however, is counteracted by the cam 14, which is caused by 50 the upward movement of the cable to impinge against the latter and bind or jam the cable between the face of the cam and the wear-block 19, whereby the portion 11 of the cable is firmly gripped and held stationary 55 relatively to the casing. It follows, therefore, that as the casing descends on the portion 10 of the cable the portion 11 of the cable is drawn down with it, and at the same 60 time the portion 10 is drawn up through the casing. When the descent has been accomplished and the sling has been detached from 65

the person, the device may be returned by merely drawing down upon the portion 11 of the cable, whereupon said portion of the cable will pass loosely between the cam and wear-block, but the frictional engagement of the pulleys with the portion 10 of the cable will cause the device to ascend therewith. 70

By providing the brake-arms with the two straight wear-strips in the manner described undue wear upon the cable is not only prevented, but we find that the force with which the cable is gripped and the speed of the descent can be much better and more promptly 80 regulated.

We have throughout the specification referred to the cable as being "endless," and have so indicated it in the drawings; but it will be evident that a single length of cable separated at the ends might be employed, and by the term "endless" we wish to be understood that such a cable is included, the term "endless" being used to indicate that the two parts 10 and 11 are formed in one piece 85 and pass over a pulley or similar guide above the casing and brake. 90

Having described our invention, what we claim is—

1. In a fire-escape, the combination with a frame or casing and a cable extending therethrough, of a friction-brake comprising two arms pivotally connected together and constructed and arranged to be spread at their upper ends by said casing. 95

2. In a fire-escape, the combination with the frame or casing rounded at its lower end and the cable passed therethrough, of the friction-brake comprising two arms pivotally connected near their lower ends and having diverging upper ends adapted to engage the rounded end of the frame or casing, substantially as described. 100

3. In a fire-escape, the combination with the frame or casing rounded at its lower end and having laterally-projecting staples secured in the opposite sides of said end, of a friction-brake comprising two arms pivotally connected near their lower ends and having divergent hook-shaped upper ends suspended 115 on said staples, said arms having their faces constructed to embrace a cable passed through the frame or casing, substantially as described. 120

4. In a fire-escape, the combination with the frame or casing rounded at its lower end and having laterally-projecting staples secured in the opposite sides of said end, of a friction-brake comprising two arms pivotally connected near their lower ends and having divergent upper ends suspended on said staples, said arms having their adjacent faces constructed to embrace a rope passed through the frame or casing, and a hook and pin arranged respectively on said arms and operating to hold the latter parallel, substantially as described and for the purpose specified. 125

5. In a fire-escape, the combination with a frame or casing, of an endless cable passing

therethrough, means carried by the casing for frictionally gripping one portion of the cable to retard the descent of the casing, means operating to grip the other portion of the cable 5 during the descent of the casing and hold the two immovable relatively to one another, but permitting the casing to freely travel thereon in an upward direction, and a friction-brake comprising two pivotally-connected arms 10 adapted to be spread at their upper ends by said casing, substantially as described.

6. In a fire-escape, the combination with a frame or casing, of an endless cable passing therethrough, means carried by the casing for 15 frictionally gripping one portion of the cable to retard the descent of the casing, a pivoted cam arranged to grip the other portion of the cable between its face and the side of the casing during the descent of the latter and 20 hold the two immovable relatively to one another, but permitting the casing to freely travel thereon in an upward direction, and a friction-brake comprising two pivotally-connected arms 25 adapted to be spread at their upper ends by said casing, substantially as described.

7. In a fire-escape, the combination with a frame or casing, of an endless cable passing therethrough, means carried by the casing for 30 frictionally gripping one portion of the cable to retard the descent of the casing, a pivoted cam, a spring for causing said cam to grip the other portion of the cable between its face

and the side of the casing during the descent of the latter, but yielding to permit the casing 35 to freely ascend, substantially as described.

8. In a fire-escape, the combination with a frame or casing, of an endless cable passing therethrough, means carried by the casing for frictionally gripping one portion of the cable 40 to retard the descent of the casing, a wear-block of non-abrading material seated in a recess in one side of the casing, and a pivoted cam arranged opposite said wear-block and operating to grip the other portion of the ca- 45 ble during the descent of the casing but permitting the latter to freely ascend thereon, substantially as described.

9. In a fire-escape, the combination with the frame or casing rounded at its lower end and 50 the rope or cable passed therethrough, of the friction-brake comprising two arms pivotally connected near their lower ends and having diverging upper ends adapted to engage the rounded end of the frame or casing, and wear- 55 strips of non-abrading material fixed to the inner adjacent faces of said arms and grooved longitudinally, substantially as described.

In testimony whereof we have hereunto set our hands in presence of two subscribing witnesses.
